*Primary Examiner—Louis Zarfas**Attorney, Agent, or Firm—Banner, Birch, McKie & Beckett*[57] **CLAIM**

The ornamental design for a cup shaped shoe sole, as shown and described.

DESCRIPTION

FIG. 1 is a side elevational view of one side of a cup shaped shoe sole showing my new design;

FIG. 2 is a side elevational view of the other side of the cup shaped shoe sole shown in FIG. 1;

FIG. 3 is a front elevational view of the cup shaped shoe sole shown in FIG. 1;

FIG. 4 is a rear elevational view of the cup shaped shoe sole shown in FIG. 1;

FIG. 5 is a bottom plan view of the cup shaped shoe sole of FIG. 1;

FIG. 6 is a cross-sectional view along the line 6—6 in FIG. 5;

FIG. 7 is a cross-sectional view along the line 7—7 in FIG. 5; and

FIG. 8 is a cross-sectional view along the line 8—8 in FIG. 5.

The broken line showing of a shoe upper in FIGS. 1-4 is for illustrative purposes only and forms no part of the claimed design.

FIG. 2

FIG. 4**FIG. 3**
